UNITED STATES PATENT OFFICE

GUY ETHAN ALLING, OF ATHOL, MASSACHUSETTS, ASSIGNOR TO ATHOL MANUFACTURING COMPANY, OF ATHOL, MASSACHUSETTS, A CORPORATION OF MASSACHUSETTS

DESIGN FOR A COATED FABRIC

Application filed June 12, 1929. Serial No. 31,641. Term of patent 3½ years.

To all whom it may concern:

Be it known that I, GUY ETHAN ALLING, a citizen of the United States, residing at Athol, county of Worcester, State of Massachusetts, have invented a new, original and ornamental Design for Coated Fabrics, of which the following is a specification, reference being had to the accompanying drawings, forming a part thereof:

The figure of the drawing is a plan view of a piece of coated fabric embodying my new design.

I claim:

The ornamental design for a coated fabric, as shown.

In testimony of which invention, I have hereunto set my hand, at Athol, Mass., on this 7th day of June, 1929.

GUY ETHAN ALLING.
